UNITED STATES PATENT OFFICE

EMIL WEINHEIM, OF NEW YORK, N. Y.

SIPHON BOTTLE

Application filed November 1, 1928. Serial No. 316,581.

This invention relates to siphon bottles or jars particularly of the type described in my copending application for Siphon bottle, Serial No. 240,062, filed December 14, 1927.

The object of the invention is to simplify the construction by means of which efficient and convenient control of both discharging charged liquid under pressure and the charging of such liquid with a compressed gas may be effected. In carrying out this object I propose to employ a single valve to control all the functioning of my siphon bottle, both for charging and discharging. A further object of the invention is to employ a discharge spout as the manipulator for controlling by its position all the valve action, and as an additional feature, the securing of the spout when in non-discharging position so as to function as a serviceable carrying handle. A further object of my invention is to reduce the cost of construction and amount of material required in the embodiment of parts capable of carrying out the function of a self-charging and discharging siphon bottle.

The above and further objects of my invention will be pointed out more particularly in the following claims which are directed to an illustrative embodiment of my invention described in the following specification in connection with the accompanying drawings solely for purposes of illustration and not limitation.

In the drawings, Fig. 1 is a plan view of my improved cap structure. Fig. 2 is a section through line II—II of Fig. 1. Fig. 3 is a vertical section taken through line III—III of Fig. 1, parts being shown in elevation and parts being broken away. Fig. 4 is a fractional view similar to Fig. 3 showing the discharge position for the discharge spout, and Fig. 5 is a top view of the siphon tube with its mounting nipple.

My cap structure A comprises a threaded flange 1 to engage about a complementary form of neck of a suitable siphon bottle such as that shown in my copending application identified above and is closed across the top by a ledge 2 upstanding from which is a cartridge housing 3 provided with a threaded

end 4 to mount the usual cartridge operator and which is capable when open of tending to force compressed gas, such as carbon dioxide gas, through the port 5.

Adjacent the end of the cartridge housing 3 is formed a valve housing 6 perforated from top to bottom and having an interior wall 7 which is cylindrical in the generic sense, but which preferably is that type of cylinder known as a conical surface with the taper extending upwardly. In the wall of this valve housing is a by-pass 8 leading upwardly from the space at the bottom of the valve housing. The cap structure in the bottom of the valve housing has a cylindrical enlargement 9 preferably threaded to take the mounting nipple 10 to which is secured in any suitable manner as by soldering and from which depends the usual siphon tube or stem 11. This threaded nipple 10 is provided with a discontinuous seating ledge 12, the opening 13 in which forms a port between the interior 14 of stem 11 and the by-pass 8.

Adapted to work within the valve housing 6 is a complementary conical valve 20 mounting at its top a discharge spout 21 which serves as an operator to swivel the valve 20. The valve 20 is provided with a duct 22 leading from the lateral port 23 and is also provided with a duct 24 leading from the port 25.

Along the top of the cartridge housing 3 is preferably provided an upstanding holding lip formation 30 adapted to cooperate with an outstanding flange or beading 31 formed about the discharge end of the spout 21 and serving to reinforce the spout 21 when it functions as a carrying handle.

In the position of the apparatus shown in Fig. 3, the port 5 is in communication with the passage 14 through the siphon stem 11 so that gas under pressure from the cartridge mounted in the cartridge housing 3 may have entrance into the liquid contained in the siphon bottle and by flowing therein under pressure effects the charging thereof. In this position the discharge spout 21 is disconnected from the liquid to be dispensed and serves as a carrying handle. The complementary conical formation of the valve 20 in the valve housing 6 is effective in resist-

ing the internal pressure of the charged liquid.

In Fig. 4, the construction is shown in discharge position in which the spout 21 has been turned 180° from its position in Fig. 3 to close the charging port 5 and open the discharge connections for the spout 21. For example, by-pass 8 is now in communication with ports 23 and 22 to effect an opening between the interior 14 of the siphon stem and the discharge spout.

It is preferred that the valve housing, cartridge housing and cap structure be fabricated as a single die casting of suitably strong metal such as a zinc or aluminum alloy.

The valve 6 may be a die casting, as likewise the nipple 10. The siphon tube 11 may be metal or glass if desired, in which case a suitable packing washer between it and the nipple 10 may be desired.

The spout 21 may conveniently be formed of a bed piece of metal tubing pressed or soldered into the valve 6.

What I claim and desire to secure by United States Letters Patent is:

1. In a cap structure for siphon bottles, combined apparatus for charging liquid and for delivering charged liquid comprising a base member, a cap enclosure provided with a single opening adapted to mount a siphon stem; an upstanding structure providing a valve housing above and communicating with said opening; means providing a cartridge mounting and being provided with a charging port leading into said valve housing; a single swiveling valve member rotatably mounted in said valve housing and carrying a discharge spout and being provided with valve ducts and valve ports capable in one position of opening communication between said charging port and said siphon stem and closing communication between said siphon stem and said discharge spout and in another position closing communication to said charging port and opening communication between said siphon stem and said discharge spout.

2. In combined charging and discharging apparatus for siphon bottles, a cap structure providing a cartridge housing and a cylindrical valve seat providing a through opening from the outside to the inside of said cap structure and having ports in its walls; a discharge spout having a rotating valve at its bottom and swiveled in said valve seat to cooperate with said ports, said valve having ports and passages alternately to establish communication between said charging housing and the liquid chamber and between said discharge spout and the liquid chamber.

3. A cap for siphon bottles having a cartridge housing and a valve housing; a siphon tube pendent from said cap and communicating with the interior of said valve housing; a single rotary valve member, a discharge spout mounted as an extension of said valve

member and constituting an operator therefor; said valve member and said valve housing being provided with cooperative ports whereby a manipulation of said spout between discharge position and charging position serves as the sole means for controlling the entrance and exit from said siphon bottle of the liquid to be dispensed and the opening of communication between the liquid to be charged and a charging cartridge.

4. In a siphon bottle, an upwardly or outwardly tapered conical valve member having control ports and passages; a combined discharge spout and handle fixed and carried by said conical valve; a valve housing providing a conical seat for said valve and having two sets of ports cooperating with said valve, the one functioning for the entrance of charging gas and the other functioning for the discharge of liquid.

5. In a siphon bottle, means for charging liquid with a gas under pressure and for discharging the charged liquid comprising means for mounting a cooperating cartridge of compressed gas; and a single valve member for controlling all fluid entrance and exit from said siphon bottle.

In witness whereof, I have signed my name to this specification, this 31st day of October, 1928.

EMIL WEINHEIM.
